Primary Examiner — George D. Kirschbaum

Assistant Examiner — Antoinette Martine Suiter

(57) **CLAIM**

The ornamental design for a thermometer with detection wire, as shown and described.

DESCRIPTION

1. Thermometer with detection wire

1.1 : Perspective

1.2 : Perspective

1.3 : Front

1.4 : Back

1.5 : Left

1.6 : Right

1.7 : Top

1.8 : Bottom

The broken lines shown in the drawings are included for the purpose of illustrating portions of the thermometer with detection wire that form no part of the claimed design.

1 Claim, 8 Drawing Sheets
